C. H. STUIVENBERG

CALCULATING MACHINE

Filed Feb. 8, 1923

UNITED STATES PATENT OFFICE.

CORNELIS HENDRICUS STUIVENBERG, OF AMSTERDAM, NETHERLANDS, ASSIGNOR, BY MESNE ASSIGNMENTS, TO NAAMLOOZE VENNOOTSCHAP KAMATEC, OF AMSTERDAM, NETHERLANDS.

CALCULATING MACHINE.

Application filed February 8, 1923, Serial No. 617,814, and in the Netherlands February 8, 1922.

The present invention relates to improvements in apparatus for adding and printing, in which the adding and printing is effected by means of cards, which are provided with 5 perforations corresponding to the amounts to be added. In machines of this kind, a certain pin can pass through the card corresponding to the position of a perforation, which brings out a stop also corresponding 10 to the number. The movement of the printing types is released over the whole length and takes place under the action of a spring. Owing to the position of the stop, the movement is limited in such a manner that the 15 type corresponding to the number will be positioned opposite the printing rollers, and that the adding mechanism, which is put into operation during the return motion, will be turned only by a number of teeth 20 corresponding to the number of the numeral printed.

The disadvantage of this arrangement is, that the movement of the types, (and consequently the movement of the adding 25 mechanism) owing to its being under the action of a spring, is dependent on the smooth working of the great number of moving parts in the machine. It has been proved, that it is only necessary for there to be a 30 slight disturbance in the smooth running of the machine for causing false impressions to be made and for the adding to be incorrect. More particularly as there is no check on the internal working of the apparatus, 35 it is exceedingly difficult to find an error that has crept in, in this manner.

According to the present invention the types are operated positively in correspondence with the position of the perforation in 40 the card. Not only is the above mentioned drawback entirely avoided in this manner, but the great advantage is obtained, that the printing can take place on the card itself as well, which gives a very effective check 45 on the correct working of the apparatus. A further advantage consists in a considerable reduction of the number of moving parts, whereby the reliability of the machine is considerably enhanced.

50 In the accompanying drawing a constructional example of the invention is shown, in which Fig. 1 is an elevation of the machine.

Fig. 2 is a similar view of the card expelling means and,

55

Fig. 3 is a fragmentary detail plan view showing several of the pivotally mounted levers and lugs forming part of the machine.

In order that the description may not be too complicated, it is assumed that the 60 card is provided with one perforation only, that is, that adding only takes place for one column of figures. By the various subsidiary parts being arranged parallel to one another, the same device can be used for an 65 addition comprising a plurality of columns. In the drawing only those subsidiary parts are shown, which are necessary for explaining the invention.

The types are indicated by the numerals 70 0, 1, 2, 3, 4, 5, 6, 7, 8 and 9, while it is assumed in the present case that the card 10 is provided with one perforation corresponding 75 to the numeral 5. The card 10 is laid on a plate 11, which is provided with ten recesses which are indicated by the numerals 0', 1', 2', 3', 4', 5', 6', 7', 8' and 9', in correspondence with the types. The card 10 is laid on the plate 11 in such a manner that the back edge rests against a projecting part 80 12 of the plate 11. The plate 11 is thereupon moved in the direction shown by the arrow (to the right), the amount of this movement always being the same and the plate at the end of the movement occupying 85 the position shown in broken lines. The plate thereupon returns to the initial position.

On the plate 11 is fixed a cross-piece 13, 90 which in the initial position of the plate presses against a double-armed lever 14, which is pivoted on a pin 16, whereby the horizontal arm of the lever raises the pin 15 against the action of a spring 17. On the plate 11 being moved in the direction of the arrow, the cross-piece 13 recedes from the lever 14 and the spring 17 presses the pin 15 down until the latter strikes the card 10. When the plate 11 has moved so far 95 that the perforation for the numeral 5 is under the pin 15, the spring 17 will press the pin 15 through this perforation into the recess 5'. As soon as the edge of the recess reaches the pin 15, the latter will be carried 100 along and the whole frame 18, with which the pin 16 is connected, will take part in 105

the movement of the plate 11 for a distance corresponding to the position of the perforation in the card. The frame 18, which, according to the present constructional example, is provided in two places with the sets of type 0-9, is guided by the pins 19. When the plate 11 has reached its extreme position, the types with the numerals 5 will be in the path of the type hammers 21 and 22, both in the case of the printing rollers 20 and of the card 10. The movements of the plate 11 are transmitted in such a manner as combined reciprocating and rotary movements to the shafts 23 and 24, on which the arms 25 and 26 are mounted, that, with the plate 11 in its extreme right hand position, the type hammers 21 and 22 can move freely under the action of the springs 27 and 28. This movement is however prevented by the arms 29 and 30, which engage with hooks 31 and 32, behind a pawl on the type hammers, until, on the plate 11 reaching its extreme position, the arms 29 and 30 are raised. At this moment the hammers 21 and 22 will therefore strike the types 5, which are capable of moving in the frame 18 against the action of springs, the numeral 5 thus being printed on the printing rollers and on the card. At this moment the adding wheel 33 is raised until its teeth engage in the teeth 34 of the frame 18.

During the return movement of the plate 11, which now takes place, the movements are as follows:—

(a) The frame 18 is carried back by the same distance, at which the types also return into the initial position.

(b) The adding wheel 33 is rotated by the teeth 34 by a number of teeth corresponding to the movement of the frame 18. By this means the number 5 is added on this wheel.

(c) On the frame 18 having returned to its initial position, the pin 15 is raised during the further movement of the plate 11 and slides along the card 10 until the cross-piece 13 strikes the lever 14. This lever strikes against the spring 17 and raises and arrests the pin 15.

(d) The arms 25 and 26, which, corresponding to the movements of the plate 11, perform a reciprocating motion about the shafts 23 and 24, carry the type hammers 21 and 22 along with them during the return movement.

(e) On the plate 11 returning to its initial position the cams, which are allowed by the arms 29 and 30 to rotate, have again come into such a position that the said arms are released again, whereby, through the engaging of the hooks 31 and 32, the type hammers are arrested, while the adding wheel 33 is again removed from the teeth 34.

The card 10 may thereupon be removed from the apparatus and it is possible to

check at once on this card whether the required number has been printed. The entirely positive control ensures the same number being printed on the printing rollers and the wheel 33 having added this number. 70

In order that the parts may act properly, a small amount of clearance must obviously be left between the pin 15 and the recesses 0'-9' of the plate 11. This clearance might however cause the position of the types at 75 the moment of printing, that is, when the plate has reached its extreme right hand position, to be not always and everywhere exactly alike and the printing not always to be in a straight line. In order to obviate 80 this drawback, a second arm 35 is mounted on a shaft 23, which is also moved to and fro. During this movement a pin 36 on the arm 35 moves through a slot 37 in a bar 38. The bar 38 is rotatably connected to a bar 85 39, which is rotatable about a fixed shaft 40. The length of the slot 37 is such that, at the end of the movement, the pin 36 will carry the bar 38 along with it and the bar 39 will be turned about the shaft 40, a stop 41 on the 90 said bar, the shape of which corresponds exactly to the teeth of the rack 34, being pressed into the space between said teeth. By adjusting this lever transmission it is easy to cause the stop 41 to bring the rack 95 34 at this moment into the correct position for all the columns and consequently the types as well, which lie in the path of the type hammers. The impressions will then be in an exactly straight line and exactly at 100 the place required. The stops 41 provided for the various columns may all be on a common bar, in which case they may form a bar corresponding to the said teeth.

Since, at the end of the forward movement 105 all the type hammers are released by means of the arms 29 and 30 being lowered and raised, there would always be as many hammers in operation as there are columns in the machine, and in instances where numbers of a few digits are to be printed, certain of the type hammers will print only the numeral 0. It is preferable, however, that no more figures should be printed than there are numerals in the number. 115

For this purpose for every column in the apparatus a double-armed lever 43 is provided, which is pivotally mounted on a shaft 42. The lever is provided with a hook 44 which, when in operative position prevents the movement of the type hammers 21 and is further provided with a stop 45 preventing the movement of the type hammers 22. This change of position is caused by a stop 46 on the said lever, which, during the movement of the frame 18 strikes against a bevelled shoulder 47 on the said frame and in this manner releases the type hammers, owing to the lever 43 being turned around the shaft 42. For this purpose each lever 43 is 120 125 130

provided with a lug 61, which, on the said lever turning, also engages and carries along with it the lever for a column having a lower base number. By this means the type hammers for all columns having a lower base number than the highest base number to be printed are released. Hence, for this column the numeral 0 can be printed straight away. In the case of the higher base numbers, however, no printing will take place as the corresponding type hammers are locked by the lever 43.

In the arrangement described, on the plate 11 moving back, the frames 18 are immediately carried along by means of the pins 15, which have penetrated the recesses in the plate 11 through the perforations. The said pins 15 are then drawn from the recesses and through the card, as soon as each frame 18 has returned into its initial position. During this operation it is possible, however, that the card may become damaged, if the pin should strike against the edge of the perforation in the card. In order to prevent this, the plate is given not only a to-and-fro motion but also an up-and-down motion. When the plate 11 has reached its extreme right-hand position, where the printing takes place, it will move downwards with the card lying on it until the pins 15 are quite clear of the recesses in the plate 11 and the perforations in the card 10. On the plate 11 moving back, the cross-piece 13 will strike against the lever 14, causing the latter to raise the pin 15 against the action of the spring 17 and to arrest it. This causes the lever to be rotated about the shaft 16 and the lever to be pressed against the frame 18, the latter being carried along by the continued return motion of the plate 11. When the plate 11 has completed its return motion, all the frames 18 will have returned into the initial position. As regards the downward movement of the plate 11 in the extreme right-hand position, after a new card 10 has been placed on it, an upward movement of the plate 11 must take place before the forward movement begins.

Instead of letting the card 10 take part in the backward movement of the plate 11 and for removing the card from the apparatus after the entire movement has been completed, the card may be held fast, as soon as the plate 11 has reached its extreme right-hand position and thus return without the card. Means must be provided for expelling the card when in this position. A suitable mechanism for this purpose is shown in Figure 2. When the plate 11 has completed its movement to the right, the card 10 is passed under leaf-springs 48 fixed to the casing of the apparatus, which cause the card to be pushed between the sets of double springs 49 and 50, also fixed to the casing.

The springs 49 and 50 grip the card 10, so that it cannot return with the plate 11.

During the forward movement an arm 51 fixed to the plate 11 engages and swings a frame 54 rearwardly against the action of the spring 52, the frame being pivotally mounted on the shaft 53. On the frame 54 rollers 55 and 56 are mounted, of which the rollers 55 are driven by means of a wheel 57 mounted on the shaft 53 in the direction shown by an arrow in Figure 2. The shaft 53 itself is given its rotary motion by a wheel 58, which is kept continuously rotating while the machine is being used.

During the return movement of the plate 11 the spring 52 draws the frame 54 back until the set-screw 59 in the said frame strikes against the cam 60. This cam is so constructed that at the moment, in which the plate reaches its extreme right-hand position and therefore all the other parts return into their initial position, the set-screw 59 will be located opposite a part having a smaller radius. In this position the springs 52 can draw the frame 54 still further back, the set-screw 59 taking up the position shown in dotted lines. The rollers 55 and 56 will be moved so far in the direction of the card that they can just grip its extreme edge. The card will then be carried along between the rollers and be ejected from the machine.

While in the above description, mention is only made of types provided with numerals, the apparatus may equally well be used for printing letters and generally in apparatus for such work.

What I claim is:—

1. In a tabulating machine adapted to take data from perforated cards, movable frames, sets of type supported by said frames, a plate movable relatively to said frames and consisting of a support for a perforated card, and means adapted to enter a perforation in a card supported on the plate during movement of the latter whereby to couple the frames with the plate for simultaneous movement.

2. In a tabulating machine adapted to take data from perforated cards, movable frames, sets of type supported by said frames, a plate movable relatively to said frames and consisting of a support for a perforated card, and means adapted to enter a perforation in a card supported on the plate during movement of the latter whereby to couple the frames and the plate for simultaneous movement, said means including a spring actuated pin carried by the frame.

3. In a tabulating machine adapted to take data from perforated cards, movable frames, sets of type supported by said frames, a plate movable relatively to said frames and consisting of a support for a perforated card, and means adapted to enter a perfo-

ration in a card supported on the plate during movement of the latter whereby to couple the frames with the plate for simultaneous movement, said means including a spring actuated pin normally projected in the direction of the plate, and means co-acting with said pin when the plate is in initial position to retract said pin to inoperative position.

couple the frames with the plate for simultaneous movement, said plate and frames being mounted for reciprocal movement and said frames being adapted to have their extent of movement varied according to the location of the perforations in the cards supported on the plate, means acting during the movement of the frames in one direction to actuate type.

10 4. In a tabulating machine adapted to take data from perforated cards, movable frames, sets of type supported by said frames, a plate movable relatively to said frames and consisting of a support for a perforated card, and means adapted to enter a perforation in a card supported on the plate during movement of the latter whereby to couple the frames with the plate for simultaneous movement, actuating means for the
15 sets of type and aligning means for the frames actuated by the type actuating means.

8. In a tabulating machine adapted to take data from perforated cards, movable frames, sets of type supported by said frames, a plate movable relatively to said frames and consisting of a support for a perforated card, and means adapted to enter a perforation in a card supported on the plate during movement of the latter whereby to couple the frames with the plate for simultaneous movement, said plate and frames being mounted for reciprocal movement and said frames being adapted to have their extent of movement varied according to the location of the perforations in the cards supported on the plate, means acting during the

5. In a tabulating machine adapted to take data from perforated cards, movable frames, sets of type supported by said frames, a plate movable relatively to said frames and consisting of a support for a perforated card, and means adapted to enter a perforation in a card supported on the plate during movement of the latter whereby to couple the frames with the plate for simultaneous movement, actuating means for the sets of type and locating means for the frame actuated by the type actuating means, said locating means including a plurality of recesses in the frames and a member movable about a fixed axis actuated by the type actuating means and adapted to enter one of the recesses.

of the recesses.

6. In a tabulating machine adapted to
40 take data from perforated cards, movable
frames, sets of type supported by said
frames, a plate movable relatively to said
frames and consisting of a support for a
perforated card, and means adapted to enter
45 a perforation in a card supported on the
plate during movement of the latter whereby
to couple the frames with the plate for
simultaneous movement, and means for mov-
ing the plate laterally away from the frames
50 as said plate and frames approach the limit
of their movement.

engage and eject the card.

9. In a tabulating machine adapted to take data from perforated cards, movable frames, sets of type supported by said frames, a plate movable relatively to said frames and consisting of a support for a perforated card, and means adapted to enter a perforation in a card supported on the plate during movement of the latter whereby to couple the frames with the plate for simultaneous movement, said plate and frames being mounted for reciprocal movement and said frames being adapted to have their extent of movement varied according to the location of the perforations in the cards supported on the plate, means acting during movement of the frames in one direction to actuate type, a locking member for the type actuating means engaged and retained in locking position by the frames while the latter occupy their initial position and means on said frames coacting on said locking member to release the latter when the frames are moved out of initial position.

55 7. In a tabulating machine adapted to take data from perforated cards, movable frames, sets of type supported by said frames, a plate movable relatively to said frames and consisting of a support for a perforated card, and means adapted to enter a perforation in a card supported on the plate during movement of the latter whereby to

In testimony whereof I have signed my ¹¹⁵ name to this specification.

CORNELIJS HENDRICUS STUIVENBERG.
